Atty.

UNITED STATES PATENT OFFICE.

EZRA RAMIN, OF BOSTON, MASSACHUSETTS, ASSIGNEE OF ONE-THIRD TO JULIUS H. WOLFSON AND ONE-THIRD TO LEWIS W. HARLEM, BOTH OF BOSTON, MASSACHUSETTS.

FOLDING WIRE EASEL.

Application filed April 2, 1927. Serial No. 180,427.

This invention relates particularly to a folding easel adapted to support cards, small pictures, phonograph records, and other articles, and to stand on a support such as a 5 show case, a table, or a shelf, or base in a show window.

The object is to provide a simple, strong and durable easel composed entirely of wire and adapted to be conveniently folded in 10 small compass, and involving the employment in its construction of a minimum quantity of wire.

Of the accompanying drawings forming a part of this specification,

15 Figure 1 is a perspective view showing my improved easel operatively adjusted or opened.

Figure 2 is an edge view of the same.

20 Figure 3 is an edge view showing the easel folded.

Figure 4 shows in perspective the pair of front legs, and the fixed member of the triangular brace hereinafter described.

25 Figure 5 shows in perspective the single rear leg.

Figure 6 shows in perspective the hinged V-shaped member of the triangular brace.

Figure 7 is a top plan view of the hinged brace member.

30 Figure 8 is an enlargement of a portion of Figure 2, a portion of the hinged member loop embracing the rear leg being broken away and shown in section.

Figure 9 is an enlargement of a portion of 35 Figure 7 and shows the portion of the rear leg shown by Figure 8.

The same reference characters indicate the same parts in all the figures.

40 12, 12 designates a pair of front legs connected at their upper ends by a neck 13 and diverging therefrom to their lower ends. The legs are provided with forwardly projecting rests 14 for an article supported by the easel, the rests being preferably formed 45 by bending backwardly the lower portions of the front legs. 15 designates a single rear leg having an eye 16 at its upper end loosely embracing the neck 13, so that the rear leg is hinged to the neck and is adapted to swing rearward from the front legs and form therewith a tripod, and toward the front legs as shown by Figure 3 to fold the easel.

The easel is provided with a triangular

brace of novel construction whereby the 55 front legs 12 may be rigidly connected and permanently spaced apart in tripod formation, a member of the brace being fixed to the front legs and another member hinged to the fixed member and slidably connected 60 with the rear leg.

The fixed member of the brace is a straight rod 17 having eyes 18 formed on its opposite ends and rigidly secured to the front legs 12 in any suitable manner, as by closely compressing the eyes on the legs or soldering them to the legs.

The hinged member of the brace is substantially V-shaped and includes 65 two arms 19 having eyes 20 at their outer ends loosely embracing the fixed member 17, 70 the latter constituting a hinge pintle on which the hinged member is adapted to swing from the inoperative folded position shown by Figure 3 to the operative position

shown by Figures 1 and 2. The arms 19 of 75 the hinged member are connected at their inner end portions by a loop 21 which, as indicated by Figure 2, is inclined relative to the arms.

In forming the arms and loop from a length of wire I prefer to cross the 80 arms as best shown by Figure 7, the arms contacting with each other where one crosses the other. The inclined loop surrounds an oblong opening 22 through which the rear leg 15 passes.

When the hinged brace member is in its operative position, the loop 21 bears at the point indicated by 23 (Figures 8 and 9), on one side of the leg, and at the point indicated by 24 on the opposite side of the leg.

The bearing points 23 and 24 are 90 at different heights as best shown by Figure 8. The loop and the rear leg are so interengaged that the loop 21 grips the leg 15 and prevents swinging of the leg in either direction (toward or from the front legs).

95 At the same time downward swinging of the hinged brace member from the position shown by Figures 1 and 2, is prevented by the rear leg. In Figure 8 I have shown a portion of the loop broken away to show the 100 location of the bearing point 23 more clearly.

When the easel is to be folded, the hinged brace member is swung upward to the inoperative position shown by Figure 3, the brace member being located between the 105 front legs and confining the rear leg 15 beside the front legs.

It will be seen that the triangular brace

rigidly connects the three legs when the hinged member thereof is in its operative position so that the legs cannot deviate from the tripod formation.

5 Owing to the fact that the rear leg is a single length of wire, the quantity and cost of the material required for the manufacture of the easel are reduced to a minimum.

I claim:

- 10 A folding wire easel comprising, in combination, a pair of front legs connected at their upper ends by a neck and diverging therefrom to their lower ends, the legs and neck being formed from a single length of wire, a rear leg having a loop at its upper end, hinged at its upper end to the neck and adapted to swing rearward from the front legs to form therewith a tripod, and toward the front legs to fold the tripod, the rear leg 15 and its loop being formed from a single length of wire, and a triangular brace composed of a straight member fixed to and ex-

tending between the front legs and spacing them apart, and a V-shaped member including arms hinged at their outer ends to the fixed member and converging to their inner ends, and a gripping loop connecting the arms and inclined relative thereto, said loop embracing and being slideable on the rear leg, the inclination of the loop being such that when the hinged brace member is swung downwardly from a folded position, the rear leg is swung rearwardly to an operative position and gripped by the loop, so that the rear leg is confined against swinging movement in either direction, and further downward movement of the loop is prevented, and when the hinged brace member is swung upwardly, the loop slides on the rear leg and locates it beside the front legs, the easel being 30 35 40 folded.

In testimony whereof I have affixed my signature.

EZRA RAMIN.
